UNITED STATES PATENT OFFICE.

BERT VAN VORCE, OF LOS ANGELES, CALIFORNIA, ASSIGNOR OF ONE-HALF TO STUART D. FRASER, OF LOS ANGELES, CALIFORNIA.

ICE-CREAM STAND.

985,309.

Specification of Letters Patent. Patented Feb. 28, 1911.

Application filed August 31, 1910. Serial No. 579,955.

To all whom it may concern:

Be it known that I, BERT VAN VORCE, a citizen of the United States, residing in Los Angeles, California, have invented a new 5 and useful Ice-Cream Stand, of which the following is a specification.

My object is to make a stand for use in selling ice cream, and the like, in the open air as at parks, picnics, beaches, street corners and the like; and my invention consists 10 of the novel features herein shown, described and claimed.

In the drawings: Figure 1 is a vertical sectional detail of an ice cream stand embodying the principles of my invention. Fig. 2 is a detail of one of the supporting legs and umbrella support as indicated by the arrow 2 in Fig. 1.

Referring to the drawing in detail, the 20 leg sockets 1 are T-shaped, the side nipples being screw threaded to receive the legs 2 and the pipe rim 3 extending loosely through the end nipples so as to hinge the legs to the rim. The main frame is an inverted cone 25 parted horizontally near the vertical center and comprising the upper shell 4 and the lower shell 5 flanged and connected together by bolts 6. The upper end of the shell 4 is connected to the rim 3 and is provided with 30 a door opening 7 and a floor 8. The door 9 is hinged to the upper edge of the lower shell 5 in place to close the opening 7 and carries the steps 10 so as to form a stairway leading to the floor 8 when the door is let 35 down.

The ice box 11 has a hub 12 at the center of its bottom and a drain pipe 13 is fixed through the hub and extends up and down there being drain openings through the 40 pipe from the bottom of the interior of the ice box. A bearing 14 is mounted upon legs

15 secured to the floor 8 and the drain pipe 13 is inserted downwardly through the bearing 14 and through the floor 8, so as to rotatably mount the ice box in the center of 45 the shell 4. A jar 16 is mounted upon the shelf 17 fixed upon the upper end of the drain pipe for containing the cornucopias 18. Light bulbs 19 are fixed to the rim 3. A nipple 20 extends upwardly from one of the 50 sockets 1 to receive the stem of the umbrella 21. The ice cream jars 22 are placed in the ice box. The operator stands upon the floor 8 and the ice box is rotatable.

The stand is readily knocked down and 55 portable.

I claim:

1. An ice cream stand comprising an inverted hollow cone, means for holding the cone upright, a floor half way up in the 60 cone, and an ice box rotatably mounted upon the floor.

2. An ice cream stand comprising an inverted hollow cone, a floor in the cone, a door leading to the space above the floor and 65 adapted to swing down and form steps, legs connected to the rim of the cone, an umbrella connected to the rim of the cone, and an ice box rotatably mounted upon the floor.

3. An ice cream stand comprising an in- 70 verted cone formed in two parts, a floor in the cone, a door leading to the space above the floor and adapted to swing down and form steps, a pipe rim around the upper end of the cone, legs hinged to the rim, an ice 75 box rotatably mounted upon the floor, a cornucopia jar mounted upon the ice box, and lights mounted upon the rim.

BERT VAN VORCE.
